(57) **CLAIM**

The ornamental design for a rocket toy, as shown and described.

DESCRIPTION

FIG. 1 is a top, front, left side perspective view of a rocket toy embodying my new design;

FIG. 2 is a bottom, rear, right side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a first exploded perspective view thereof;

FIG. 10 is a second exploded perspective view thereof; and, FIG. 11 is an enlarged view of the selected portion 11 in FIG. 7.

The broken lines shown in the figures depict portions of the rocket toy that form no part of the claimed design. The dot-dash broken lines represent boundaries of the enlarged portions and form no part of the claimed design.

1 Claim, 11 Drawing Sheets
